(57) **CLAIM**

The ornamental design for a base for modular product display system, as shown and described.

DESCRIPTION

FIG. 1 is a perspective view of the new base design; FIG. 2 is front elevational view thereof; FIG. 3 is a rear elevational view thereof; FIG. 4 is a left elevational view thereof; FIG. 5 is a right elevational view thereof; FIG. 6 is a top plan view thereof; FIG. 7 is a bottom plan view thereof; FIG. 8 is an exemplary perspective view of the base of FIG. 1 and which further shows a product display assembly mounted on the base; FIG. 9 is an exemplary perspective view of the base of FIG. 1 and which further shows a variation of the product display assembly of FIG. 8 further including a retracted drawer; and, FIG. 10 is an exemplary perspective view of the base of FIG. 1 and which further shows a variation of the product display assembly of FIG. 8 further including an extended drawer. The broken lines in the drawings represent portions of the base for the modular product display system that form no part of the claimed design. Dot-dash-dot lines of the product display assembly in FIGS. 8-10 are used to illustrate exemplary environment of use.

1 Claim, 10 Drawing Sheets
